REVOLVING TOOL RACK

Bela B. Nevai, Dobbs Ferry, N.Y., assignor to Nevco Wood Products Co., Inc.

Filed Sept. 14, 1970, Ser. No. 24,955

Term of patent 14 years

Int. Cl. D6—01

U.S. Cl. D33—17

FIG. 1

FIG. 2

FIG. 3

FIG. 4

FIG. 1 is a top plan view of a revolving tool rack embodying my new design;

FIG. 2 is a front view of such rack;

FIG. 3 is a bottom plan view of the rack; and

FIG. 4 is a side view of the rack.

I claim:

The ornamental design for a revolving tool rack, as shown.
